TOMATO BASKET OR SIMILAR ARTICLE

William W. Wright, Oak Park, Ill.

Application June 9, 1954, Serial No. 30,873

Term of patent 14 years

(Cl. D58—26)

Fig. 1 is a side elevational view of a tomato basket showing my new design;

Fig. 2 is a top plan view thereof;

Fig. 3 is an end elevational view thereof taken from the left side of Fig. 1; and

Fig. 4 is a cross-sectional view thereof, taken on the line 4—4 of Fig. 2.

I claim:

The ornamental design for a tomato basket or similar article, as shown.
